CLAIM

The ornamental design for a housing for a graphic telephone, as shown and described.

DESCRIPTION

FIG. 1 is a top front perspective view of a housing for a graphic telephone, showing my new design;
 FIG. 2 is a rear perspective view thereof;
 FIG. 3 is a reduced front elevation view thereof;
 FIG. 4 is a top plan view thereof;
 FIG. 5 is a right side elevation view thereof;
 FIG. 6 is a left side elevation view thereof;
 FIG. 7 is a rear elevation view thereof;
 FIG. 8 is a bottom plan view thereof; and
 FIG. 9 is a perspective view, similar to FIG. 1; the broken lines representing the telephone handset and light pen are shown for illustrative purposes only.

FIG. 1.

FIG. 2.

FIG. 3.

FIG. 4.

FIG. 5.

FIG. 6.**FIG. 7.****FIG. 8.**

FIG. 9.
